C. F. LEFEVER,
LIQUID GUN,
APPLICATION FILED DEC. 18, 1915.

1,180,858.

Patented Apr. 25, 1916.

Attorney.

UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

LIQUID-GUN.

1,180,858.

Specification of Letters Patent. Patented Apr. 25, 1916.

Application filed December 18, 1915. Serial No. 67,526.

To all whom it may concern:

Be it known that I, CHARLES F. LEFEVER, a citizen of the United States of America, residing at Plymouth, in the county of

5 Wayne and State of Michigan, have invented certain new and useful Improvements in Liquid-Guns, of which the following is a specification, reference being had therein to the accompanying drawings.

10 The invention relates to liquid guns of that type in which the liquid is ejected by the telescopic collapsing of the barrel and in which a storage is provided for a plurality of shots.

15 The invention comprises the peculiar construction and arrangement of parts as hereinafter set forth.

In the drawings: Figure 1 is a longitudinal section through the gun; Fig. 2 is an elevation thereof showing the manner of charging the gun; Fig. 3 is a cross section on line $x-x$ Fig. 1; and Fig. 4 is a view similar to Fig. 1 showing the magazine barrel fully charged.

20 25 The construction specifically illustrated is that of a liquid pistol, in which A is the frame member formed of a sheet-metal stamping having complementary sections abutting against each other and forming both barrel and handle.

25 30 B is a telescopic extension of the barrel slidably engaged therein, and having a trigger and guard section C formed integral therewith, this member also being preferably a sheet-metal stamping with abutting complementary sections.

35 D is a magazine barrel arranged within the extension barrel B and frictionally engaging the same so as to be movable therewith. The length of this barrel D is greater than the telescopic movement of the barrel B, and the clearance within the outer frame member A is sufficient to permit a longitudinal adjustment of the barrel D in the member B while still permitting the telescopic movement.

40 45 E is a piston engaging the barrel D and provided with a tubular stem F which extends to the outer end of the member B, to which it is anchored, said tube forming the discharge conduit for the liquid.

50 55 G is a ratchet bar secured to the barrel D and H is a pawl pivotally secured within the member A and engaging said ratchet. The pawl H is preferably embraced by the

opposite side flanges of the trigger and guard member C, and is thereby guided and held from lateral displacement in relation to the ratchet.

I is a sleeve engaging the frame member A and longitudinally adjustable thereon.

J is a pin engaging the barrel D and extending outward therefrom through longitudinal slots K in the frame member A into engagement with inwardly extending shoulders L on the sleeve member I. The arrangement is such that rearward movement of the sleeve member I upon the frame member A will carry with it the pin J in the slots K, thereby moving the barrel D 65 rearward in relation to the frictionally-engaging extension barrel B. To permit of the rearward movement of the barrel D as just described, the pawl H must be disengaged from the ratchet G. This is automatically effected by movement of the sleeve I through the medium of a finger M projecting from the pawl and engaging a cam portion N on the sleeve. In normal position said finger M is in a notch O in the 70 sleeve, which permits the pawl H to engage the ratchet, a spring P engaging the pawl serving to hold the parts in this position. When, however, the sleeve is drawn rearward the cam N engaging the finger, first 75 80 disengages the pawl, after which the movement of the sleeve will carry the pin J and barrel D rearward to the limit of the space within the member A.

Q is a spring engaging a guide rod R 90 within the handle member and serving to yieldably press the extension member B forward.

In operation, supposing the parts to be in the position shown in Fig. 1, the piston E 95 is at the rear end of the barrel D, so that all the liquid is ejected therefrom. To charge the barrel, the end of the tube is immersed in liquid and the sleeve I is then drawn rearward, which by releasing the pawl H and carrying backward the barrel D will move the latter relative to the piston E and fills it with liquid. After thus loading, the sleeve I is returned to its original position, which releases the finger M 100 105 and permits the pawl H to engage the ratchet G. Thus, whenever the trigger is actuated to collapse the extension barrel B, this will cause a rearward movement of the piston E, while the barrel D is held from 110

such movement by the pawl H engaging the ratchet G, so that a portion of the liquid is ejected. On the return movement the barrel D being in frictional engagement with the barrel B and being released from the pawl H will be moved forward. At the completion of this movement the pawl H engaging with another tooth of the ratchet will again hold the barrel D from rearward movement, so that a second shot may be fired, and this action can continue until all of the liquid is exhausted.

What I claim as my invention is:—

1. In a liquid gun, the combination with a false barrel, of a magazine barrel and co-operating piston therein, externally-operable means for relatively moving said magazine barrel and piston to charge the latter with liquid, and a reciprocating trigger mechanism for relatively moving said piston and magazine barrel step-by-step in the opposite direction to successively discharge portions of the liquid contents.

2. In a liquid gun, the combination with a false barrel, of a magazine barrel longitudinally movable therein, a piston in said magazine barrel, a reciprocating trigger mechanism for moving said piston within said barrel to eject portions of the liquid contents, externally-operable means for moving said magazine barrel to greater distance than the reciprocation of said trigger to charge the same with liquid for a plurality of shots, and means for holding said magazine barrel stationary during the ejecting movement of said piston and permitting movement with said piston in the return of said trigger mechanism to step-by-step advance the said magazine barrel.

3. In a liquid gun, the combination with a telescopically collapsible false barrel, of a magazine barrel adjustable within said false barrel for a distance greater than the telescopic movement, a piston in said magazine barrel connected to the movable member of said telescopic barrel, externally-operable means for moving said magazine barrel relatively to said piston to draw in a liquid charge for a plurality of shots, and means for holding said magazine barrel stationary during the ejecting movement of said piston, permitting movement with said piston in the opposite direction.

4. In a liquid gun, the combination with a telescopically collapsible false barrel and a reciprocatory trigger mechanism for collapsing and expanding said barrel, of a magazine barrel frictionally engaging the movable member of said false barrel, a piston engaging said magazine barrel fixedly connected to said movable member, externally-operable means for moving said magazine barrel in relation to said piston to draw in a liquid charge, and means for holding said magazine barrel stationary during the

collapsing movement of said false barrel, permitting movement with said false barrel during the expanding movement thereof.

5. In a liquid gun, the combination with a telescopically collapsible false barrel and a reciprocatory trigger mechanism for actuating the same, of a magazine barrel within and frictionally engaging the movable member of said false barrel, being of greater length than the length of the collapsing movement, a piston engaging said magazine barrel and fixedly attached to said movable member, a slideable sleeve embracing said telescopic barrel, connected with said magazine barrel and operable to move the latter relative to said piston to draw in a liquid charge, and means operable during the reciprocation of said trigger mechanism for holding said magazine barrel from movement in one direction and permitting movement in the opposite direction.

6. In a liquid gun, the combination with a telescopically collapsible false barrel and a reciprocatory trigger mechanism for actuating the same, of a magazine barrel frictionally engaging the movable member of said telescopic barrel, a piston engaging said magazine barrel, and discharge tube leading from said piston to the end of the movable member of said telescopic barrel and connected thereto, means for holding said magazine barrel from movement by said trigger mechanism in one direction while permitting movement in the opposite direction, and means for moving said magazine barrel to charge the same, adapted in its operation to release said holding means and to permit the engagement of said holding means at the completion of its operation.

7. In a liquid gun, the combination with a telescopically collapsible false barrel and a reciprocatory trigger mechanism for actuating the same, of a magazine barrel frictionally engaging the movable member of said false barrel, a piston engaging said magazine barrel secured in fixed relation to said movable member, a pawl engaging notched bearings on said magazine barrel to hold the same from movement with said trigger in the collapsible movement of said barrel, while permitting movement therewith in the opposite direction, a sleeve member slideable on said telescopic barrel connected with said magazine to move the same for charging with liquid, and means operating upon the adjustment of said sleeve for disengaging said pawl to permit the movement of said magazine and for reengaging said pawl on the return of said sleeve.

8. A liquid gun, comprising a stamped sheet-metal barrel having a handle section integral therewith and a stamped sheet-metal extension barrel section telescopically engaging said first-mentioned section and having an integral trigger and guard section

formed by parallel plates embraced by said handle, a magazine barrel frictionally engaging said extension barrel and longitudinally adjustable therein, a piston engaging 5. said magazine barrel, and connected fixedly to said extension barrel, a pawl mounted in said handle embraced by the parallel flanges of said trigger and guard section, and engaging notched bearings on said magazine 10 barrel to hold the same from movement, a sleeve embracing the outer barrel connected

with said magazine barrel to adjust the same, and a finger on said pawl having a cammed engagement with said sleeve to disengage the pawl from said magazine when 15 the latter is adjusted by said sleeve.

In testimony whereof I affix my signature in presence of two witnesses.

CHARLES F. LEFEVER.
